CLAIM

The ornamental design for a mobile phone, as shown and described.

DESCRIPTION

1. Mobile phone

1.1 is a front perspective view of a mobile phone;

1.2 is a front view thereof;

1.3 is a back view thereof;

1.4 is a left view thereof;

1.5 is a right view thereof;

1.6 is a top view thereof;

1.7 is a bottom view thereof; and

1.8 is a back perspective view thereof.

The broken lines depict portions of the mobile phone that form no part of the claimed design; the dash-dot broken lines define the boundary of the claimed design and form no part thereof.

1 Claim, 8 Drawing Sheets
